US0D1073693S

(12) **United States Design Patent** (10) Patent No.: **US D1,073,693 S**
 Huang et al. (45) Date of Patent: ** *May 6, 2025

(54) **DISPLAY SCREEN OR PORTION THEREOF WITH ICON**

(71) Applicant: **Google LLC**, Mountain View, CA (US)

(72) Inventors: **Hank H. Huang**, Menlo Park, CA (US); **Alex Tursi**, Seattle, WA (US); **Elbert Tiao**, Diamond Bar, CA (US); **Jane Yoon**, Brooklyn, NY (US); **Byeong Chae Cho**, Mountain View, CA (US); **John Schlemmer**, Redmond, WA (US); **Soyoung Park**, Milpitas, CA (US); **Sarah Goldschmidt**, Seattle, WA (US); **Hannah Cho**, Oakland, CA (US)

(73) Assignee: **GOOGLE LLC**, Mountain View, CA (US)

(*) Notice: This patent is subject to a terminal disclaimer.

(**) Term: **15 Years**

(21) Appl. No.: **29/873,411**

(22) Filed: **Mar. 30, 2023**

(51) LOC (15) Cl. **14-04**

(52) U.S. Cl.

USPC **D14/495**

(58) **Field of Classification Search**

USPC D14/485-495

CPC G06F 3/048-04897

See application file for complete search history.

(57) **CLAIM**

The ornamental design for a display screen or portion thereof with icon, as shown and described.

DESCRIPTION

The sole FIGURE is a front view of a display screen or portion thereof with icon, showing our new design.

The dot-dash broken lines in the FIGURE show a display screen or portion thereof, and form no part of the claimed design.

1 Claim, 1 Drawing Sheet
